UNITED STATES PATENT OFFICE

153,858

DESIGN FOR A TOP FOR VEHICLE BODY

Norman D. Cosner, Tecumseh, Mich., assignor to
 Meyers Aircraft Company, Tecumseh, Mich., a
 corporation of Michigan

Application April 28, 1947, Serial No. 138,656

Term of patent 14 years

(Cl. D14—27)

To all whom it may concern:

Be it known that I, Norman D. Cosner, a citizen of the United States, residing at Tecumseh, in the county of Lenawee and State of Michigan, have invented a new, original, and ornamental Design for a Top for Vehicle Body, for which the following is a specification, reference being had to the accompanying drawings, forming part thereof, in which:

Fig. 1 is a rear perspective view of the top for vehicle body, showing my design.

Fig. 2 is another perspective view thereof.

The side of the top for a vehicle body not shown in Fig. 1 is identical with the side thereof which is shown.

The dotted line showing in the several drawing figures is for illustrative purposes only.

I claim:

The ornamental design for a top for vehicle body, substantially as shown and described.

NORMAN D. COSNER.
